UNITED STATES PATENT OFFICE.

GEORGE W. HARRIS, OF KINGSTON, NEW YORK.

APPARATUS FOR MANUFACTURE OF GAS.

SPECIFICATION forming part of Letters Patent No. 536,078, dated March 19, 1895.

Application filed October 24, 1891. Serial No. 409,716. (No model.)

To all whom it may concern:

Be it known that I, GEORGE W. HARRIS, a citizen of the United States, residing at Kingston, in the county of Ulster and State of New York, have invented certain new and useful Improvements in the Manufacture of Illuminating-Gas; and I do hereby declare the following to be a full, clear, and exact description of the invention, such as will enable others skilled in the art to which it appertains to make and use the same.

This invention relates to the manufacture of combustible gas.

The object of the invention is to combine gas from bituminous coal with water-gas in such manner that a very large proportion of the illuminants usually lost in the manufacture of coal-gas by the ordinary methods will be absorbed by the water-gas, and then as requisite, combine this gas with rich gas from oil or naphtha.

The object is, furthermore, after all or nearly all the illuminating gases have been driven off from coal, to utilize the residual coke for the manufacture of water-gas, and mix this with coal-gas, or poor coal-gas and with oil-gas, and fix the mixture into a permanent gas.

With these objects in view, the invention consists in making a combined gas from bituminous coal and water-gas, diverting the gas from the stand-pipe of the coal-retort, the stand-pipe having a slight seal or dip for the purpose, making a rich gas from oil or naphtha and steam in an oil-retort, and allowing the mixed gases from the bituminous coal and water-gas to pass into the oil-retort and mingle with the oil-gas, and then pass progressively back and forth through a part of this retort until the whole mixture is properly fixed, that is, combined into a permanent gas which then passes off through the stand-pipe and oil-retort, all as carried into effect by the particular apparatus, hereinafter described and claimed.

Referring to the drawings: Figure 1—is a view in front elevation, showing the chief portion of the apparatus as put together, a portion of the front wall being broken away with removal of the mouth-pieces of the oil-retorts more perfectly to illustrate the arrangement of the different parts, particularly

the construction of the double retorts, the steam-heaters, and the oil-retorts, with the divisions in the mouth-piece; and Fig. 2—is a view in central, longitudinal section of a portion of one of the oil-retorts.

The apparatus may be described, generally, as consisting of two or more double retorts, two or more steam-heaters, and one or more oil-retorts, all to be made, preferably, of the best fire-clay material and completely enamelled inside and out. I have shown an arrangement with two double retorts, two steam-heaters, and two oil-retorts.

The double retorts, which are fully described in the patent granted to me November 9, 1875, No. 169,637, are to be used in the same manner as therein described, but, the lower chamber being filled with anthracite coal or coke, the upper one is charged with bituminous coal, and when the anthracite coal or coke is heated to incandescence, water-gas is produced by admission of highly superheated steam in fine jets up through the false bottom of tile, the water-gas then passing up through the perforated diaphragm into the upper section of the retort containing the charge of bituminous coal in suitable quantity, say from two hundred to three hundred pounds, the gas from which is mixed with the water-gas as it is forced into the upper compartment, whereby less rich tar is produced than in the ordinary method, as the water-gas charges itself with the illuminants; but, while a very much larger quantity of gas may thus be produced from a given amount, yet, unless a very rich or cannel coal be used, the illuminating power may not be as high as desired. It is to remedy this that the oil-retort is provided. This oil-retort, composed of several flues or chambers of suitable size, is placed in the upper part of the bench, and is protected by tiles from excessive heat. Into this retort, vaporized oil or naphtha is introduced from a long, bent pipe kept hot by being situated close to the bench, yet outside of the arch where it will be at a lower heat than the retort, the oil or naphtha being first injected into the pipe by a jet of superheated steam. The mixture from the oil and steam passes back and forth through the first portion of the oil-retort, and, coming to the front, into a lower chamber of the mouth-piece, it meets and

is introduced into the upper section of the retort, the oil or naphtha being first injected into the pipe by a jet of superheated steam. The mixture from the oil and steam passes back and forth through the first portion of the oil-retort, and, coming to the front, into a lower chamber of the mouth-piece, it meets and

mingles with the water-gas and coal-gas from the coal-retorts, in any desired proportion, the whole mixture than passing through a second portion of the oil-retort, and being converted 5 into a fixed gas, when it escapes through a stand-pipe at the oil-retort. This operation is repeated, the coke being drawn from the upper compartment of the coal-retort, and a fresh charge of coal being supplied to the 10 upper compartment, over the fire, every six or more hours, or as may be requisite, and more or less oil or naphtha being used, according as the illuminating power is to be greater or less.

15 Referring to the drawings, A, A, indicate two double retorts; a indicating the openings in the false bottom for the admission of superheated steam into the lower compartment charged with coke or anthracite coal heated to 20 incandescence; a^2 , indicating the perforated partition between the lower compartment and the upper compartment, which upper compartment is charged with bituminous coal. From the coal-retort, there is a stand-pipe, 25 a^3 , which has a slight seal or dip, and through this stand-pipe, either the heaviest bituminous coal gas may be taken off, which will commence distilling before the anthracite coal in the lower compartment is heated to incandescence, should bituminous coal be put into the upper chamber at the beginning, or the 30 mixed water-gas and coal-gas may be taken off through this pipe, if the resultant gas is sufficiently rich for the purpose required. If 35 not, however, the gas is diverted from this stand-pipe through a pipe, a^4 , provided with a stop and regulating-valve, a^5 , the purpose of which pipe and valve will be presently described.

40 B indicates a superheater for the steam employed to pass into the incandescent coke and to inject the oil and mix it with the gas as requisite, as will be presently described.

The water used in generating the steam is 45 supplied through a pipe, b , to a return-pipe, b^2 , located below the furnace and, from the latter pipe, steam passes, by a pipe, b^3 , to the superheater, from which, by pipe, b^4 , it may be admitted to the false or perforated bottom 50 of the lower compartment of the coal retort, and, by a pipe, b^5 , to the oil-feed, as will presently appear.

In the upper part of the bench are oil-retorts, C, C, corresponding with the retorts, A, 55 A, each oil-retort consisting of several flues or return-pipes, c , c^2 , c^3 , c^4 , and being protected from excessive heat by tiles, c^5 . These flues connect in pairs, vertically, at the rear; and, at the front of the retorts, that is, in the 60 mouth-pieces, are vertical partitions, c^6 , between the flues, c , and c^4 , of each retort, a horizontal partition, c^7 , between the upper and the lower flues of both retorts, and a vertical partition, c^8 , below, between the two retorts, forming divisions in the mouth-piece and separating them into an upper chamber 65 for each retort, a lower chamber for each re-

tort and a middle chamber, common to both retorts. Each flue, c , opens out of the upper outer chamber of the mouth-piece; each flue, 70 c^2 , opens into the lower chamber of the mouth-piece at its retort; each flue, c^3 , opens out of the lower chamber of the mouth-piece at its retort; and each flue, c^4 , opens out of the middle chamber of the mouth-piece. Into each 75 lower chamber of the mouth-piece also opens one of the pipes, a^4 .

A long, bent pipe, c^9 , preferably of iron, is placed close to the bench where it will become hot, but outside of the arch, so that it 80 will be subjected to a heat lower than that of the retorts. One of these pipes may be at each side of the bench, and enters the upper, outer chamber of the mouth-piece. At the other end of this pipe, an injector supplies 85 oil or naphtha by highly superheated steam, the steam coming through the pipe, b^5 , and the oil through a pipe, c^{10} . The oil-bench has a stand-pipe, c^{11} , over the middle chamber of the mouth-piece, and is unsealed. Upon opening the valve in the pipe, a^4 , the mixed coal and water-gas enters the lower compartment of the mouth-piece of the oil-retort and, there meeting the current of oil-gas from the flue, c^2 , then passes, together with the oil-gas, 95 through the flue, c^3 , around into the flue, c^4 , and the mixture being fixed in its passage, escapes to the stand-pipe, c^{11} .

It will be seen that the two upper outside flues in each of the oil-retorts receive the oil 100 and steam together, and this mixture, first entering the long, bent pipes, the heat there is sufficient to vaporize most of it, especially when naphtha is used. As the gas from the oil and steam comes out of the pipe, c^2 , it 105 meets the gas coming from the retorts and all goes in through the flue, c^3 , together, coming out of c^4 , and then going up the stand-pipe, the operation being the same for both of the sets of two or more return-pipes on each side 110 of the oil-retort. The proper direction to the current of gas is given by the closed back ends of the return-pipes and the partitions in the mouth-piece.

The water-gas and poor coal-gas from the 115 retort, A, when the valve is open, pass up the pipe, a^4 , into the lower chambers in the mouth-piece, into which the flues a and a^3 open. In its passage through the flues, the 120 gas is fixed.

The supply of oil or naphtha may be so regulated that oil-gas can be made at any time during the burning off of the charge of bituminous coal, or only during the latter part of the time when the gas is of poor quality, just 125 as it may be desired to keep the total gas made of a suitable illuminating power.

Having thus fully described my invention, what I claim, and desire to secure by Letters Patent, is—

1. The combination with a double coal-retort, consisting of two compartments, the upper one to contain bituminous coal, and the lower one anthracite coal or coke, and to be 130

supplied with superheated steam, this retort having an independent stand-pipe, of an oil-retort having a stand-pipe, and a pipe between the upper compartment of the coal-retort and the oil-retort, this pipe being provided with a valve, upon the opening of which the gas generated in the coal-retort will be diverted from the stand-pipe of the coal-retort and will pass into the oil-retort, and whereby coal and water-gas may be made alone, or may be enriched by oil-gas, substantially as described.

2. The combination with the double retort, of the oil-retort, consisting of a number of flues and having a mouth-piece divided into 15 chambers into and from which the flues open, and connections between the same, substantially as described.

In testimony whereof I affix my signature in presence of two witnesses.

GEORGE W. HARRIS.
